UNITED STATES PATENT OFFICE

CHARLES W. BRAY, OF PITTSBURG, PENNSYLVANIA, ASSIGNOR TO
AMERICAN TIN PLATE COMPANY, OF ORANGE, NEW JERSEY, A
CORPORATION OF NEW JERSEY.

METHOD OF ROLLING PLATES AND SHEETS.

No. 825,634.

Specification of Letters Patent.

Patented July 10, 1906.

Application filed February 9, 1903. Serial No. 142,446.

To all whom it may concern:

Be it known that I, CHARLES W. BRAY, of Pittsburgh, Allegheny county, Pennsylvania, have invented a new and useful Method of Rolling Plates and Sheets, of which the following is a full, clear, and exact description, reference being had to the accompanying drawings, forming part of this specification, in which—

10 Figure 1 is a diagrammatic plan view of apparatus arranged in accordance with my invention. Fig. 2 is a diagrammatic side elevation of the same. Fig. 3 is a top plan view of the squaring-up and shear mechanism for a pack. Fig. 4 is a side elevation of the squaring-up and pusher mechanism for the shears; and Fig. 5 is an end elevation, partly in section, of the pack adjusting and shearing mechanism.

20 My invention relates to the rolling of black plates or sheets, and is designed to lessen the labor and reduce the cost of producing such sheets or plates.

In the drawings, referring to Figs. 1 and 2, 25 2, 3, and 4 are heating-furnaces into which the bars are fed through rear openings 5. The bars, which are heated in the furnaces in a continuous manner, are pushed out through the front openings 6 to feed-tables 7, leading 30 to a feeding apparatus 8 at the entrance to the continuous or tandem mill. The first portion of this mill I have shown as consisting of six sets of rolls 9, 10, 11, 12, 13, and 14, arranged in tandem with suitable feeding devices 35 between them. The metal bars after passing singly and successively through these fixed passes, pass between feed-rollers 16, which are driven and which feed the metal into the matching mechanism 17. This matcher is 40 preferably arranged as shown and described in my copending application, Serial No. 141,320, filed January 31, 1903, and from it the pack is fed out between feed-rolls 18 and into two further sets of tandem rolls 19 and 20, ar- 45 ranged in line with the first set with suitable feed mechanism 15 between them. The pack formed in the matcher is rerolled in the succeeding sets, and is thus elongated to a length which is undesirable for finish-rolling,

50 and I sever the pack transversely before re-heating for finishing. Thus, as shown in Figs. 3, 4, and 5, the pack issuing from the rolls 20 is carried forward by parallel

sprocket-chains 21 over supporting-plates 22, and thence by successive chains 23 and 24 55 over the separated supports 25 and 26. The pack is thus fed forward until the front ends of the sheet strikes stop-fingers 27, depending from a rack-bar 28, supported in overhead guides 29. The rack-actuating pinion 30 60 also engages another oppositely-extending rack-bar 31, having a depending finger 32, which may swing forwardly, as indicated in dotted lines in Fig. 3, but is stopped against swinging backwardly beyond a vertical position. The bearings 33 for the rack 31 and an overhead frame 34, preferably consisting of those for the rack 28 are both carried from a channel secured to a cross-bar on the housings, with its outer end carried on supports 35, 70 within which may be mounted a shaft 36, having a sprocket-wheel connected by chains 37 with a sprocket on the shaft, carrying the pinion 30. The shaft 36 carries a hand-wheel by which the fingers 27 and 32 may be 75 simultaneously moved toward or away from each other, and after the ends of the pack have been stopped by fingers 27 the operator actuates the hand-wheel to draw the fingers toward each other, and thus center up the pack 80 and bring it into correct position relative to the shears. In the transverse spaces between the carrying sprocket-wheels for the chains 21, 23, and 24 and beyond the last sprocket-wheel I provide three pushers 38, which consist of hollow slides movable on transverse rods 39 and carrying bent and pivoted push-fingers 40. The lower parts of the slides are 85 connected by pivotal links 41 with lever-arms 42, which project from a common shaft 43, 90 which is rocked by hand-lever 44. When the hand-lever is pushed forward, the push-fingers will act upon the side edge of the pack and force it forwardly within flaring guides 45, leading to the rotary shears. 95

I have shown the shear-blades as being five in number, the outer ones trimming the edges, while the inner ones divide the pack into four packs. These rotary shear-blades 46 are secured to the shafts 47, supported in suitable bearings 48, the shear-blades working through slots in the guide 45. In front of the rotary shears are placed feed-out rollers 49, which feed out the severed packs. These packs slide down the inclined chute 50 and 100 drop upon the tilting support 51 of truck 52.

The packs thus formed are taken to suitable reheating-furnaces and the pack reheated and then finished by rolling upon a single finishing-mill, if thinner gages are desired.

- 5 I preferably match either two or three plates in the matching device to form the pack. After shearing this rolled pack, if it is three-ply and heavy sheets are to be formed, I preferably heat and finish-roll the pack as it is sheared with these three layers. If lighter gages are to be formed, I prefer to either shear the pack of twice the length desired and then double each pack before finish-rolling or to pile together two or three of the cut
- 10 packs to form a pack of a larger number of layers for finish-rolling.

The advantages of my invention result from the shearing of a pack of sheets, thus reducing the number of handlings and, further, from rolling, forming a pack, rerolling the pack, and then shearing the rolled pack to form the packs, which are then reheated and finished on the ordinary single finishing-mill.

- 15 20 25 Many changes may be made in the form

and arrangement of the apparatus without departing from my invention.

I claim—

1. The method of rolling black plates or sheets, which consists in producing a plurality of plates of a gage suitable for forming into a pack, then matching the plates to form a pack, rolling the matched pack, shearing the pack transversely, and then finishing each severed pack without repiling; substantially as described.

2. The method of rolling black plates or sheets, consisting in rolling the plates separately, forming a pack, rolling the pack, shearing the pack transversely, reheating the severed packs, and finishing each pack on a single finishing-mill; substantially as described.

In testimony whereof I have hereunto set my hand.

C. W. BRAY.
